A. COSTA.
CARBURETER

APPLICATION FILED FEB. 11, 1915.

1,184,696.

Patented May 23, 1916.

UNITED STATES PATENT OFFICE.

ANTHONY COSTA, OF CLEVELAND, OHIO, ASSIGNOR OF FOUR-TWENTIETHS TO FRED J. KELLER, FOUR-TWENTIETHS TO HENRY J. MUEHLHAUSER, AND THREE-TWENTIETHS TO WILLIAM FAHEY, ALL OF CLEVELAND, OHIO, AND FIVE-TWENTIETHS TO JAMES BOYLE AND TWO-TWENTIETHS TO AMOS McGRAW, BOTH OF YOUNGSTOWN, OHIO.

CARBURETER.

1,184,696.

Specification of Letters Patent.

Patented May 23, 1916.

Application filed February 11, 1915. Serial No. 7,488.

To all whom it may concern:

Be it known that I, ANTHONY COSTA, a citizen of the United States, and a resident of Cleveland, county of Cuyahoga, and State of Ohio, have invented a new and useful Improvement in Carbureters, of which the following is a specification, the principle of the invention being herein explained and the best mode in which I have contemplated applying that principle, so as to distinguish it from other inventions.

The present improvements relate in general to means for vaporizing liquid fuels and more particularly to the provision of a device generally known as a carbureter for vaporizing hydrocarbon fuels such as gasoline and kerosene, and mixing the same with air for use in an internal combustion engine.

In my improved apparatus I have eliminated the necessity for a float chamber, which added considerable cost and size to the common types of carbureters, and was the source of occasional trouble by reason of the float valve sticking or leaking, thus causing improper regulation of the flow of the liquid to the fuel supply nozzle in the mixing chamber. In my improved device I have provided means for automatically and positively cutting off the fuel supply except when the engine is in operation. During such operation the supply of fuel is regulated according to the speed of the engine, and is proportioned to the amount of air that is being drawn through the apparatus, thus providing a constant and proper proportion between the amounts of gas and air which are consumed.

To the accomplishment of the foregoing and related ends, said invention, then, consists of the means hereinafter fully described and particularly pointed out in the claims.

The annexed drawing and the following description set forth in detail certain mechanisms embodying the invention, such disclosed means constituting, however, but one of various mechanical forms in which the principle of the invention may be used.

In said annexed drawing: Figure 1 is a vertical section through my improved apparatus; Fig. 2 is an enlarged section on the line 2-2 Fig. 1; Fig. 3 is a section on the

line 3-3, Fig. 1; Fig. 4 is a horizontal section on the line 4-4, Fig. 1, and Fig. 5 is a partial section taken on the same plane as 55 that of Fig. 1, but showing a modified type of valve.

In Fig. 1 there is shown a mixing chamber 1, which may be of any suitable type, in which there is provided an upstanding circular flange or collar 2. Threaded into the upper end of such collar 2, is a fuel supply nozzle 3 including a hollow disk 4 having radially disposed apertures 5 leading respectively to a number of vertically disposed holes 6 formed in the outer periphery of the disk through which the primary air supply is adapted to be drawn. It will be unnecessary to describe in greater detail the construction of the fuel supply nozzle as 70 any desired type of nozzle may be used, the present type being illustrated merely for the purpose of showing one of various efficient means for vaporizing the fuel.

The chamber formed in the collar 2 is 75 connected at its lower end with fuel supply conduit 7, which leads directly to the main supply reservoir, thus supplying fuel to the nozzle under considerable head by reason of the height of the fuel tank above the 80 height of the carbureter. The aperture through the fuel nozzle is normally closed by means of a plunger 8 attached at its upper end to the rocker arm or link 9 pivoted upon the pin 10 and connected at its other 85 end to a rod 11 which passes through a guide formed in the side of the chamber and is provided at its lower end with a disk 12. Against this disk there is disposed a spring 13, which operates against a pivoted arm 14. The outer end of this pivoted arm is in contact with a rod 15 upon which there is mounted a valve 16 normally seated by means of a rather weak spring 17 operating against a lock nut 18 upon the top of the 95 rod.

The mixing chamber 1 is provided with a lateral extension 20 in the bottom of which there is formed a port 21 adapted to supply the primary air to the mixing chamber. 100 The air from such port 21 passes up through the passage 22 in such chamber around the collar 2 and through the apertures 6 thus vaporizing the fuel, provided any fuel is

supplied to the radial conduits 5. Auxiliary air is supplied to the mixing chamber through a port 25 formed in such extension 20 such port being normally closed by means 5 of the valve 16 attached to the rod 15. The exact construction of this valve and of the mechanism connecting the valve and the plunger closing the fuel supply nozzle have not been described in detail as the same are 10 no part of the present invention, being clearly described and claimed in a co-pending application of mine Serial No. 878,861, filed December 24, 1914. For the purpose of the present description it will only be 15 necessary to state that the auxiliary air valve 16 is normally maintained on its seat by a slight pressure exerted by the spring 17. The other springs which are shown, such as the spring 13 and springs 26 and 27, serve 20 to take up any looseness in the connections, but are so balanced that they have little or no effect on the operations of the connecting mechanism between the plunger and the auxiliary air valve. There is provided a 25 plate 70 lying across the opening 21, and forming a bearing for the rod 15.

When the engine to which the present carbureter is attached is cranked, the suction of the pistons in the cylinders tends to draw 30 air through the mixing chamber of the carbureter, such air being supplied primarily by the port 21. During this operation auxiliary air valve 16 is closed and closure of this valve seats the plunger 8 thus completely closing the fuel supply nozzle and 35 preventing the admission of fuel to the mixing chamber. The area of the primary air port 21 is relatively small and when the engine is cranked even at a slow speed this 40 port does not admit sufficient air to the mixing chamber to maintain the normal or atmospheric pressure therein. This reduced pressure in the mixing chamber permits the greater atmospheric pressure without to 45 open the auxiliary air valve 16 which in turn raises the plunger 8, thus admitting fuel to the hollow center of the disk 3 and thus by way of the passage 5 to the vertical conduits 6 through which the primary air 50 passes. The primary air then vaporizes the liquid fuel and the same is mixed with this air and remixed with the auxiliary air which passes up through the mixing chamber outside of a circular wall or flange 28 55 formed therein. The tension of the spring 17 may be adjusted by means of the nut 18 for any desired operation of the engine. The auxiliary air and the primary air do not mix until they reach the mixing chamber 1 since 60 the ports 21 and 25 are separated in the extension 20 by a wall 30. In this manner it is possible to entirely eliminate the usual float chamber, since there is a positive closure for the fuel supply nozzle when the 65 engine is not operating, while during oper-

ation of the same the area of the fuel supply nozzle is directly and automatically proportioned to the area of the auxiliary air port and therefore the proportion of air and fuel is properly regulated at all speeds. 70

In Fig. 5 I illustrate a modification of the auxiliary air valve in which the valve 31 is provided with a flange 32 which prevents admission of air until a sufficient decrease in pressure in the mixing chamber has been 75 secured to move the valve a certain distance against the pressure of the spring 17.

My improved apparatus eliminates one defect in the operation of the existing types of carbureters which has been a source of 80 trouble in starting and in accelerating the engine to which the carbureter was attached. The physical work required to draw the air into the cylinders of the engine was increased by reason of having to also raise the 85 level of the liquid fuel in the spray nozzle a certain distance, since obviously the normal level in the nozzle had to be below the discharge level to prevent overflow. This difficulty was most apparent and constituted 90 a real defect upon starting the motor. In my device upon the opening of the valve in the nozzle, the pressure on the liquid therein forces it up and outward into and across the path of the incoming air. The flow of liquid 95 is instantly responsive to the opening of the nozzle valve but in no way affects the operation of the remainder of the device nor increases the burden on the engine with the result that the engine starts rapidly and 100 smoothly and can be accelerated in speed in the same manner.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In a carbureter, the combination of a mixing chamber provided with an air opening, a valve normally closing such opening and opened upon the decrease in pressure in 115 said chamber, and a fuel nozzle mounted in said chamber, resilient means normally closing each of said valves, and other resilient means connecting said valves and adapted to normally tend to maintain each in closed 120 position, said means being also adapted to correlate opening movement of said valves.

2. In a carbureter, the combination of a mixing chamber provided with an air opening, a valve normally closing such opening 125 and opened upon the decrease in pressure in said chamber, a fuel nozzle mounted in said chamber, separate resilient means normally closing each of said valves, and other resilient means normally tending to main- 130

tain said valves in closed position and adapted to correlate opening movement of said valves.

3. In a carbureter, the combination of a mixing chamber provided with an air opening, a valve normally closing such opening and opened upon the decrease in pressure in said chamber, a fuel nozzle mounted in said chamber, a spring operating against each of said valves to normally maintain it in closed position, a member attached to each of said valves for opening the same, said members having a resilient one-way connection therebetween, permitting correlation of the movements of said valves.
4. In a carbureter, the combination of a mixing chamber provided with an air opening, a valve normally closing such opening and opened upon the decrease in pressure in said chamber, a fuel nozzle mounted in said chamber, said valve opening upon movement in opposite directions, a lever connected to such nozzle valve, a second lever bearing at its free end against such air valve, a rod connected to said first named lever on the other side of its axis from said nozzle valve and a spring operating against

said rod and said second lever and arranged to normally exert pressure tending to close both said valves.

5. In a carbureter, the combination of a mixing chamber provided with an air opening, a valve normally closing such opening and opened upon the decrease in pressure in said chamber, a fuel nozzle mounted in said chamber, a valve normally closing said nozzle said valves opening upon movement in opposite directions, a lever connected to such nozzle valve, a second lever bearing at its free end against such air valve, a rod connected to said first named lever on the other side of its axis from said nozzle valve, springs adapted to normally seat each of said valves, and another spring operating between said rod and said second lever and arranged to correlate movement of said valves.

Signed by me, this 9th day of February 1915.

ANTHONY COSTA.
